CHARLES R. PATTERSON, OF BIRMINGHAM, ALABAMA.

NUMBERING-MACHINE FOR PRINTING-PRESSES.

1,224,279.

Specification of Letters Patent.

Patented May 1, 1917.

Application filed September 29, 1916. Serial No. 122,921.

To all whom it may concern:

Be it known that I, MINDER A. COURTNEY, a citizen of the United States of America, residing at Birmingham, in the county of 5 Jefferson and State of Alabama, have invented certain new and useful Improvements in Numbering-Machines for Printing-Presses, of which the following is a specification.

10 My invention relates to automatic numbering machines for printing presses.

The object of my invention is to adapt such numbering machines as used on flat bed or platen presses to print the numerals 15 of the number in a color different from that of the general form and to accomplish this end by making only one impression and without change or modification of the press itself or its normal inking arrangements.

20 My preferred manner of accomplishing my object is to adapt the frame carrying the numeral dials to recede below type high level during the pass of the inking roll and to be automatically raised to type high level by 25 the action of the cylinder or platen so that by means of a ribbon the numerals can be printed in any color contrasting with the rest of the printed matter. The depression of the plunger carrying the prefix "No." by

30 the printing platen or cylinder to automatically advance the dials step by step is the means I prefer to use to raise the dials into printing position. I also provide an ink font and rollers for inking the numbering 35 ribbon which can be blocked in conveniently in the frame, the rollers being moved by the plunger to advance the ribbon.

These arrangements are those which I prefer, but I claim broadly to be the first 40 to adapt a numbering machine to do two color work of the character described without change in the press, and as it will enable me to print checks, tickets, transfers and like two color work, which now requires 45 two impressions and two set ups, with a single impression and set up, I thus save one half of the labor and time now required for such work. I desire to claim as part of my present invention any such adaptation of 50 the numbering machine as will enable it, by means of any individual inking means, to print its numerals of a different color from the general form.

The preferred embodiment of my invention is illustrated in the accompanying

drawings which form a part hereof, and in which:—

Figure 1 shows my improved two color printing numbering machine and its individual inking apparatus in plan.

60 Figs. 2 and 3 are sectional views taken on the lines 2—2 and 3—3, respectively, of Fig. 1.

Similar reference numerals refer to similar parts throughout the drawings.

65 The numbering machine which I have adapted for use in accordance with my invention is of the type customarily used by printers, and comprises a main U-shaped frame having end walls 1 and 3 and a base 70 2 which extends beyond the wall 3 and forms the bottom of the compartment 4 for a depressible plunger 5. The plunger is normally raised by a spring 6 resting on the bottom 2 below the plunger, and I provide 75 in its inner side face a transversely elongated slot 7 which receives a pin 8 on the upper end of a crank arm 9 mounted to rotate on a journal pin 10 which rocks in a bearing in the end wall 3 of the main frame and is 80 eccentrically connected or jointed to the cylinder 11 upon which are rotatably mounted the numeral printing dials 12. As shown there are six of these dials which are juxtaposed and each provided with a ratchet 85 wheel 13, each ratchet wheel being engaged on one side by a dog 14 and on the opposite side by a pawl 15 which is pressed against the ratchet wheel by its spring 16. The several dogs 14 are mounted rigidly upon a 90 spring pressed shaft 17 which is journaled in the walls 1 and 3 of the frame, the dogs, in the manner well understood, being of different length and set at different angles so as to effect the proper step by step advancing 95 of the type dials during the operation of the machine. The pawls 15 and springs 16 however are mounted on a floating frame 18 which is also U-shaped and comprises vertical end walls 19 and 20, which walls fit 100 loosely between the walls 1 and 3 of the main frame and have circular openings therein to receive and rest on to the ends of the type dial cylinder 11. This floating frame is provided with an arcuate slot 21 105 which receives a guide pin 22 fast in the wall 3 and adapted to hold the floating frame in upright position as it is vertically shifted by the eccentric action of the cylinder 11 when the latter turns about the cen-

ter of its supporting bearing pins 10. As shown in Fig. 1, the side wall of the plunger is cut away at 23 to receive the lever 9 and permit the latter to rock about its bearing 10 5 as the plunger rises and falls, and in thus moving to raise and lower the floating frame from full line to dotted position, Fig. 2. The plunger carries a type 24 for printing the prefix "No." of the same color as that 10 used on the inking roll of the press. Each of the type dials carries the type numerals from 0 to 9 arranged *seriatim* thereabout and adapted in the manner well understood to be advanced step by step beginning with 15 the numeral dial of lowest order and carrying from dial to dial as impressions are taken and the plunger 5 is reciprocated, each reciprocation serving to increase the number by one.

20 It is not the purpose of my present invention to claim any special features or changes in respect of this well understood method of operating the dials of a numbering machine, my object being to modify it 25 only to such extent as is necessary to adapt it to perform new and additional functions in respect of two color work. Heretofore the reciprocation of the plunger 5 by the printing cylinder or platen has served to 30 rock the floating frame 18 in such manner as to cause the resetting of the dials by the dogs 14 to print serially increasing numbers. My preferred arrangement for adapting the numeral dials to print in a 35 different color from that of the plunger type consists in the provision of an endless inking ribbon 25 which passes over the several dials and then about a guide roll 26 mounted at the lower right hand corner of 40 the floating frame. From this point the ribbon passes under the main frame through a guide way 27 and thence passes around a roll 28 journaled on a removable bearing pin 29 which is mounted in an extension 45 casing 30 that carries the inking font 31 and the ink drum 32 and the ink roll 33, which are respectively journaled on removable bearing pins 34 and 35. After passing around the roll 28 the ribbon passes under 50 a gravity acting take-up roll 36 which is mounted on the free end of a pivoted lever 37, and thence passes above the dogs 14 to the type dials. The drum 32 and roll 28 are hard metal rolls and the intermediate inking roll is a composition roll. The font is mounted to swing about a pivot pin 38 and by means of set screws 39 is pressed against the drum 32 so as to apply a thin surface coating only of the ink thereto, in the manner well understood in this art. A hinged 55 top cover 40 overhangs and protects the ink font. The casing 30 forms a substantial continuation of equal width with the main frame 2 and has at its end an extension 41, 60 equal in length to the plunger casing so

that it can be conveniently blocked in the printing frame. The drum 32 is fast on its journal pin 34 which has mounted on its outer end a ratchet wheel 42 and a rocking lever 43 carrying a pawl 44 disposed to engage the ratchet which turns with the roll and advance both counter-clockwise as the lever is rocked. The lever 43 is pivotally connected by a link 45 to a stud 45^a on the near upper corner of the floating frame 18 and the parts are so designed that the upward swinging movement of the floating frame and dials toward their printing position will retract the pawl 44 sufficiently to engage a succeeding tooth on the ratchet 70 wheel 42 and on the spring pressed return of the floating frame from printing position the pawl will advance the inking drum 32 one step and the rolls 33 and 28 will be rotated at the same time and the ribbon 75 both inked and advanced. To aline and facilitate the connection of the frame of the numbering and inking machines either of such frames is provided with dowel pins 46 in its end walls and the other frame is provided with dowel pin holes. The link 45 is readily disconnectible at either end, and by the removal of set screws 47 the journal pin 29 of the end roll 28 can be slipped out, thus permitting the roll to be removed and 80 the ribbon to be released, whereupon the two frames can be disconnected.

85 In operation, the font 31 is filled with ink of the desired color, generally red, and after the inking and numbering machine 100 frames have been connected by their dowel pins, the ribbon 25 is passed about the numbering machine parts in the manner desired and the roll 28 is inserted in position so as to press the ribbon against the roll 33 while 105 the take-up roll 36 holds it at the desired tension. The plunger 5, as is well understood, projects substantially above type high lever and as the type dials, when in 110 their lower position, are substantially below the type high lever, it follows that the passage of the yielding inking roll over the numbering machine will neither depress the plunger nor ink the ribbon over the type dials. When the impression cylinder or 115 platen however engages the plunger its spring 6 is overcome and the plunger is depressed to type high level and in so moving it acts through the connections described to raise the floating frame and the type dials 120 also into type high position when they will print through the ribbon upon the sheet, the number being in the color of the ribbon and not of the inking roll. Immediately 125 upon the release of the plunger, its spring 6 raises the latter and lowers the type dials in advance of the next passage of the inking roll and at the same time the movement of the floating frame, through the link 45 and ratchet connections, will serve 130

to turn the inking rolls and advance the ribbon step by step. The inking ribbon has enough slack to provide for the relative movements between the roll 28 and the type 5 dials, this slack being taken care of and the tension maintained by the take-up roll 36. It thus follows that with a single impression the prefix "No." and the numeral will be printed in different colors and without any modification of the press.

It is of course within the contemplation of my invention that these same results may be accomplished by other than the preferred means which I have described and I do not 15 desire to be limited to the details of construction shown but to claim as my invention as follows:

1. In an apparatus of the character described, a plunger adapted to be fully depressed only by the printing element of a 20 press, numeral type dials, mechanism controlled by the reciprocatory movements of the plunger to prevent the inking of the type dials by the press inking mechanism when the plunger is raised and to present the dials for coöperation with the printing element of the press when the plunger is lowered, and mechanism for inking the dials.

2. In a two-color printing numbering machine for presses, the combination of a plunger depressible by the printing element of a press, numeral dials which are relatively adjusted by said plunger and which set normally below the type high level, 35 mechanism controlled by the depression of the plunger for raising the dials to type high level, and a separate inking means for the dials, substantially as described.

3. An automatic numbering machine attachment for printing presses, comprising a frame carrying a depressible plunger element, numeral type dials mounted for bodily movement in the frame, mechanism for relatively adjusting the dials by the plunger 45 movements, mechanism controlled by the depression of the plunger to raise to type high level the dials which are normally below such level, and means to ink the type on the dials.

4. In an automatic numbering machine attachment for printing presses, the combination of a main frame, a spring supported depressible plunger therein, a floating frame, type dials journaled in the floating frame, 55 means controlled by the movements of the floating frame to relatively adjust the dials, means controlled by the depression of the plunger to elevate the floating frame and present the dials in printing position, and 60 means for inking the dials, substantially as described.

5. In an automatic numbering machine attachment for printing presses, a main frame carrying a depressible spring supported 65 plunger, a floating frame having journaled

therein a series of type dials, means controlled by the plunger for moving the dials into printing position, automatic mechanism for relatively advancing the dials to serially change the numbers to be printed, an inking 70 ribbon movable over the dials, and mechanism for inking the ribbon, substantially as described.

6. An automatic numbering machine attachment for printing presses comprising a type bearing depressible plunger, a spring to support the plunger, type bearing movable dials, mechanism to cause said dials to rise when the plunger is depressed and vice versa, an endless inking ribbon movable over 80 the dials, and mechanism adjacent to the numbering machine and adapted to both feed and ink the ribbon, substantially as described.

7. In an apparatus of the character described, a main frame carrying a spring supported, depressible type bearing plunger, type dials, a bearing on which the dials are rotatable, means controlled by the plunger movement to raise and lower the dial bearing, and means to ink the dials, substantially as described.

8. In an apparatus of the character described, a main frame carrying a depressible, spring supported, type bearing plunger, 95 type dials, a bearing on which the dials are rotatable, eccentric means controlled by the plunger movements to raise and lower the dial bearing, and means to ink the dials, substantially as described.

9. In an apparatus of the character described, a main frame carrying a depressible spring supported plunger, a crank mounted on the main frame and having a sliding connection with the plunger whereby it is 105 rocked by the vertical movements of the plunger, a type dial cylinder eccentrically connected to said crank, type dials mounted to rotate on said cylinder, mechanism to relatively adjust the dials, and mechanism to 110 ink the dials, substantially as described.

10. In combination, a numbering machine for printing presses comprising a main frame, a floating frame movably mounted in the main frame, a spring supported plunger 115 in the main frame depressible by the printing element of the press and adapted to control the movements of the floating frame, type dials mounted in the floating frame, mechanism responsive to the movements of 120 the floating frame for relatively adjusting the dials, an endless printing ribbon passing over the dials and under the main frame, an extension casing, feeding and inking mechanism for the ribbon mounted in said casing, 125 means to connect said casing to the main frame, and tension means to take up the slack of the ribbon, substantially as described.

11. In combination, a numbering machine 130

comprising a main frame having a bottom 5
slideway for the ribbon, a plunger and floating frame mounted in the main frame and having operating connections, printing dials
5 mounted in the floating frame, an endless ribbon passing over the dials and under the main frame, an inking attachment for the main frame comprising a removable roll about which the ribbon passes, a slack take-
10 up for the ribbon, and mechanism operable responsive to the movements of the dials for both feeding and inking the ribbon.

12. The combination with a numbering machine having its type dials vertically
15 movable and a plunger controlling the movements of the dials, of an inking attachment comprising rolls actuated responsive to the plunger movements, and an endless ribbon for inking the dials which is passed be-

tween adjacent rolls, substantially as described.

13. The combination with a numbering machine having a plunger and dials which are relatively adjustable by the plunger movements, plunger controlled means to move the dials into and below type high level, a ribbon movable about the dials, an attachment comprising a casing detachably connected to the numbering machine and comprising an inking font and inking rolls, 30 and mechanism responsive to the plunger movements for moving the rolls between two of which said ribbon passes, substantially as described.

In testimony whereof I affix my signature. 35
MINDER A. COURTNEY.
